Attorney

UNITED STATES PATENT OFFICE

JOHN S. GILFILLEN, OF KANSAS CITY, MISSOURI

AUTO TRUNK

Application filed October 25, 1929. Serial No. 402,350.

My invention relates to trunks in general and more particularly to that type which is adapted to be carried on the running board or upon a rack at the rear of an automobile, and one object is to provide a trunk of this character to the interior of which access may be more readily had than with trunks having the usual lid hinged to the upper portion of the trunk.

10 A further object is to provide a trunk of this character with a slidable door, so that access may be had to the interior of the trunk without disturbing the spare tire mounted at the rear of the automobile. Another object is to construct the trunk and the door in such manner as to provide a rain and dust-proof joint around the door when the latter is in closed position.

Another object is to provide a trunk with 20 a slidable false bottom upon which suitcases or other luggage may be stacked and slid inwardly or outwardly without becoming scratched or otherwise damaged as when placed upon or removed from a stationary bottom.

A further object is to provide a trunk which may be manufactured at low cost, and one which is strong and durable and well adapted for the purpose intended.

30 In order that the invention may be fully understood, reference will now be had to the accompanying drawings, in which:

Figure 1 is a perspective view of the trunk with the door in closed position.

35 Fig. 2 is a perspective view of the trunk with the door removed.

Fig. 3 is a detail perspective view of the door in a reverse position to that disclosed by Fig. 1, to show the rear side of the door.

40 Fig. 4 is a cross section of the trunk on line 4—4 of Fig. 1.

The main portion of the trunk consists of a top wall 2, a bottom wall 4, end walls 6 and 8, and a back wall 10. The front portion of the trunk is provided with vertical and horizontal plates 12 and 14, respectively. The plate 12 is secured to the top, bottom and end walls 2, 4 and 6, respectively, while the plate 14 is secured to the top and end walls 2 and 8, respectively, and to the plate 12.

16 designates a slidable door for normally closing the opening 18 in the front portion of the trunk. Said door 16 is provided at its lower portion with parallel longitudinal flanges 20 and 22 which are spaced apart to admit a rail 24 secured to the front portion of the bottom wall 4 and the rear portion of the plate 12. The upper portion of the door is provided with a longitudinal flange 26 which operates between the horizontal plate 14 and a horizontal rail 28. The rail 28 parallels the plate 14 and is secured to the latter and the inner surface of the top wall 2. One end of the door 16 has a vertical flange 29 and its opposite end has a vertical flange 30 extending at right angles to the door and adapted to fit in a countersunk portion 32 of the end wall 8. The countersunk portion 32 is provided near its lower end with a slot 34 in which the flange 22 of the door is adapted to operate. Handles 36 are secured to the door 16 to facilitate the opening and closing of the latter and a stop 37 is secured upon the flange 22 for contacting the inner surface of the countersunk portion 32 to limit the opening of the door 16.

38 designates a slidable false bottom mounted on slides 39 in the lower portion of the trunk and equipped with a handle 40 so that it may be slid inwardly or outwardly with suitcases or other luggage placed upon said false bottom.

With the trunk arranged as shown and described it is apparent that when the door 16 is in closed position dust and rain will be excluded from the interior of the trunk by the flanges, 20, 22, 26 and 30 on the door and the plates 12 and 14 on the front portion of the trunk.

The false bottom 38 provides a convenient support for several suitcases or other luggage which may be placed upon or removed from said false bottom when the latter is drawn outwardly, without scratching or otherwise marring said suitcases or luggage. Said false bottom 38 also supports the suitcases above the bottom wall 4 of the trunk so that they will not become scratched or otherwise damaged by any grit or other abrasive.

substance which may accumulate upon said bottom wall 4.

From the foregoing description it is apparent that I have provided a trunk embodying the advantages above pointed out, and while I have shown and described one form of the invention I reserve the right to all other forms and modifications thereof as properly fall within the spirit and scope of the invention as claimed.

Having thus described my invention, what I claim and desire to secure by Letters Patent, is:

1. A trunk having an opening through which access may be had to its interior, a horizontally disposed plate interposed between the top of the trunk and the top of said opening, an upper horizontally disposed rail arranged in the rear of and paralleling said plate, a lower horizontally disposed rail secured to the trunk at the lower portion of the opening, a slideable door for closing the opening and provided with a longitudinally disposed flange at its upper portion which is slidably mounted between the plate and the upper rail, and longitudinally disposed flanges at the lower portion of the door and straddling said lower rail.

2. A trunk having an opening through which access may be had to its interior, a vertical plate at one end of said opening, a countersunk portion in the wall of the trunk at the opposite end of the opening, a slideable door for closing said opening, a vertical flange at one end of said door and set backwardly from the front surface of the latter to fit against the rear surface of the vertical plate when the door is in closed position, and a vertical flange at the opposite end of the door and extending at right angles to the latter to enter the countersunk portion when the door is closed.

In testimony whereof I affix my signature.
JOHN S. GILFILLEN.
